(57) **CLAIM**

The ornamental design for a tangential non-dimensional interface module, as shown and described.

DESCRIPTION

FIG. 1 is a perspective view of a tangential non-dimensional interface module as used in a wall divider assembly;
FIG. 2 is an exploded perspective view thereof;
FIG. 3 is a close-up perspective view of the tangential non-dimensional interface module of FIG. 1 in isolation;
FIG. 4 is a front elevational view thereof;
FIG. 5 is a left elevational view thereof;
FIG. 6 is a right elevational view thereof;
FIG. 7 is a top plan view thereof;
FIG. 8 is a bottom plan view thereof; and,
FIG. 9 is a rear elevational view thereof.

The dotted lines represent environmental matter for illustrative purposes only, and form no part of the claimed design.
